J. A. B. SMITH

TYPEWRITING MACHINE

Filed July 31, 1923

Fig. 2.

UNITED STATES PATENT OFFICE.

JESSE A. B. SMITH, OF STAMFORD, CONNECTICUT, ASSIGNEE TO UNDERWOOD TYPE-WRITER COMPANY, OF NEW YORK, N. Y., A CORPORATION OF DELAWARE.

TYPEWRITING MACHINE.

Application filed July 31, 1923. Serial No. 654,811.

To all whom it may concern:

Be it known that I, JESSE A. B. SMITH, a citizen of the United States, residing in Stamford, in the county of Fairfield and 5 State of Connecticut, have invented certain new and useful Improvements in Typewriting Machines, of which the following is a specification.

This invention relates to improvements in 10 fan-fold or continuous billing typewriting machines, such as disclosed in the Wernery & Smith patent, dated March 16, 1915, No. 1,132,055. The plies of continuous work-sheets or fan-folded webs are threaded be- 15 tween carbon-holding blades and are thus interleaved with the carbon-sheets which are fastened to the blades. The leading end of the web or pack is fed forwardly and underneath and around the platen to be typed 20 upon.

Sometimes it becomes desirable for the same typist to work with two different lengths and kinds of work-sheet units. An 25 object of the invention is to provide im- proved means whereby two separate packs of continuous work-sheets or dissimilar fan-folded webs may be used successively or alternately.

To this and other ends, there is provided 30 means whereby two fan-fold webs or separate packs of sheets may be carried simultaneously in a machine, and either pack used at will exclusively of the other. In carrying out the invention, the packs or webs are 35 superposed, and each pack is provided with its own set of carbon-sheets and blades therefor.

Each pack is retained upon the carbon-carrier, to move idly therewith when the 40 other pack is being typed line by line. When the upper pack is to be typed, the forward end of the lower pack is first withdrawn from the platen and folded back, and its end is tucked back in a pocket which is 45 prepared to receive it, this pocket being far enough back so that the fold of the lower pack will not rest at such a point as to foul the paper-guiding devices on the typewriter carriage, when the carbon-carrier is pulled 50 forward. This pocket underlies the top pack or web, so that, while the lower web is folded back into said pocket, the top pack may be carried around the platen and typed, regardless of the lower pack, which simply

moves to and fro with the carbon-carrier. 55 When the bottom pack is to be typed, it is pulled out of the pocket and then introduced around the platen; while the forward end of the top pack is withdrawn from the platen and folded back over the carbon- 60 blades out of the way, so that it will move forward and back idly with the motion of the carbon-carrier.

In order to secure this result, the carbon-blades (of which there may be six or more, 65 although only two or three are illustrated) of the superposed pack are mounted above said pocket. The position of the latter may be between the blades of the upper set and the lower set of blades. The pocket is made 70 spacious, and the upper set of blades may rest either directly over the lower set of blades or somewhat back thereof, as may be desired.

Other features and advantages will here- 75 inafter appear.

In the accompanying drawings,

Figure 1 is a longitudinal sectional view of a continuous billing machine, showing 80 the invention applied thereto, and showing two packs of continuous work-sheets or fan-folded webs threaded therein, the lower pack being in use and the upper pack folded back out of the way.

Figure 2 is a view similar to Figure 1, ex- 85 cept that it shows the upper pack in use and the lower pack folded back into the pocket.

A displaceable platen 3 may be mounted as usual in a swing-frame 4 to oscillate about a transverse shaft 5 secured at its 90 ends in a carriage 6, and may be rotated by means of either a platen knob 7 (attached to a platen-knob shaft 8, to which is attached a spur gear 9, which rotates a similar spur gear 10, mounted on a platen shaft 11, 95 through a spur pinion 12 mounted on the transverse shaft 5), or ordinary line-space mechanism 13. Feed-rolls 14 and 15 may be used to co-operate with a rear paper-table 16 in feeding work-sheets underneath 100 and around the platen 3. A front paper-table 17 may support a gage-bar 18, on which may be mounted a gage or gages 19 for gaging the length of work-sheet units to be torn from work-sheets. The swing-frame 4 may be retained in normal position by means of a hook 20, which engages a pin 21 105 on the swing-frame.

Supported by means of brackets 22 fastened to the rear of the carriage 6 may be a usual work-supporting frame 23, a rear end member 24 of which may support, by means of brackets 25, a work support 26, which may be fitted with paper-gages 27. Usual side members 28 of the work-presenting frame 23 are fitted with rails 29 on which may be supported, by means of rollers 30, a 10 carbon-carrier 31.

Mounted upon a base 32 of the carbon-carrier 31 is a set 37

of carbon-holding blades 38, of which there 15 may be six or more, although only two are illustrated. These are mounted individually upon supports 39, one on each side of the base 32. A pack 40 of continuous work-sheets 40^a is brought over the work-support 20 26 and may be threaded through the carbon-holding blades 38, to be interleaved with carbon-sheets 40^b which are attached thereto.

These work-sheets in pack 40 may be 25 carried forward and down around the platen 3 and typed in the usual manner, the platen being swung up preparatory to straightening out the sheets, as usual, for facilitating the backward shifting of the 30 carbons between the sheets when the carbon-carrier is pushed by the handle 32^a as usual.

During the typing of the pack 40 there is held in the typewriting machine another 35 pack 49 of sheets 49^a, this pack, however, being idle and not extending to the platen, being folded back over a second set 45 of carbon-blades 46, which carry the interleaved carbons 49^b for this pack. These 40 carbon-blades 46, of which there may be six or more (only two being shown), are carried upon an elevated support 47 mounted upon the carbon-carrier 31. As shown at Figure 1, the forward end of the top 45 pack is folded back at 49^c, so that by reason of its weight the folded-back portion rests upon the pack and upon the carbon-blades, where it travels idly back and forth with the carbon-carrier during the typing of the 50 lower pack 40.

Whenever desired, the lower pack may be withdrawn from the platen and its forward portion folded back, as at 40^c, Figure 2, preparatory to unfolding the top pack 49 55 and passing it forward to and around the platen 3, as at Figure 2.

For the reception of the folded-back part of the under pack, there is provided a pocket X, Y, above the set of carbon-blades 37 and below the set of carbon-blades 45, the spaces between the brackets or supports 47 being sufficient to accommodate the width of the folded-back pack. In order to secure the desired vertical 60 amplitude for the pocket, the carbon-blades

46 are mounted at a great elevation with respect to the carbon-blades 38. The carbon-blades 46 with their support may be placed either directly above the set of carbon-blades 37, or a little in rear thereof, as 70 shown at Figure 2, the latter being the preferred form, since, by setting this upper set considerably back of the lower set, the space between the sets is much enlarged in a horizontal direction, to facilitate the introduction of the end of the pack of sheets thereinto. 75

Whenever desired, the upper pack 49 may be withdrawn from the platen and folded back, as at Figure 1, and the lower pack 80 again carried around the platen for typing thereon.

Thus by a compact and simple device provision is made whereby the packs may be used in alternation as required, and as 85 many forms may be typed and torn off from each pack as desired, while the other pack is carried idly to and fro by the carbon-carrier.

Variations may be resorted to within the 90 scope of the invention, and portions of the improvements may be used without others.

Having thus described my invention, I claim:

1. In a typewriting machine, in combination, a revoluble platen mounted in a displaceable swing frame, a movable carriage to support said swing frame, feed-rolls to co-operate with said platen, a work-presenting frame having a work-sheet support on its rear end mounted in the rear of said carriage, and a movable carbon-carrier mounted upon said work-presenting frame, comprising a plurality of groups 95 each consisting of a plurality of carbon-holding blades with carbon-sheets attached thereto, the upper and lower of said groups being spaced far enough apart vertically and horizontally to provide a spacious opening therebetween which leads to a capacious 100 pocket formed between two packs of continuous work-sheets or fan-folded webs when the latter are led over said work-sheet support and threaded through said 105 carbon-holding blades of said groups, the 110 bent-back leading end of the lower of said packs resting in said capacious pocket upon the body of said lower pack to permit the unhampered operation of the upper of said 115 packs when the latter is being used in the manner of continuous billing.

2. In a typewriting machine, in combination, a revoluble platen mounted in a displaceable swing frame, a movable carriage to support said swing frame, feed-rolls to co-operate with said platen, a work-presenting frame having a work-sheet support on its rear end mounted in the rear of said carriage, and a movable carbon-carrier mounted upon rails on said work-presenting frame, 120 125 130

comprising a base on which is mounted a plurality of groups each consisting of a plurality of carbon-holding blades with carbon-sheets attached thereto, the upper and lower 5 of said groups being spaced far enough apart vertically and horizontally to provide a spacious opening therebetween which leads to a spacious pocket formed between two packs of continuous work-sheets or fan-folded webs when the latter are led over said

work-sheet support and threaded through said carbon-holding blades of said groups, the bent-back leading end of the lower of said packs resting in said spacious pocket 15 upon the body of said lower pack to permit the unhampered operation of the upper of said packs when the latter is being used in the manner of continuous billing.

3. In a typewriting machine, in combination, a revolute platen mounted in a displaceable swing frame, a movable carriage to support said swing frame, feed-rolls to co-operate with said platen, a work-presenting frame having a work-sheet support on 20 its rear end mounted in the rear of said carriage, and a movable carbon-carrier mounted by rollers upon rails on said work-presenting frame, comprising a base furnished with an operating handle and on which is mounted a plurality of groups each consisting of a plurality of carbon-holding blades with carbon-sheets attached thereto, the upper and lower of said groups being spaced far enough apart vertically and horizontally to 25 provide a spacious opening therebetween which leads to a spacious pocket formed between two packs of continuous work-sheets or fan-folded webs when the latter are led over said work-sheet support and threaded 30 through said carbon-holding blades of said groups, the bent-back leading end of the lower of said packs resting in said spacious pocket upon the body of said lower pack to permit the unhampered operation of the upper of said packs when the latter is being used in the manner of continuous billing.

4. In a typewriting machine, in combination, a revolute platen mounted in a displaceable swing frame, a movable carriage to support said swing frame, feed-rolls to co-operate with said platen, a work-presenting frame having a work-sheet support on its rear end mounted in the rear of said carriage, and a movable carbon-carrier mounted 50 by rollers upon rails on said work-presenting frame, comprising a base furnished with an operating handle and on which is mounted a plurality of groups each consisting of a plurality of carbon-holding blades with carbon-sheets attached thereto mounted step-fashion, the upper and lower of said groups being spaced far enough apart vertically and horizontally to provide a spacious opening therebetween which leads to a spacious 55 pocket formed between two packs of con-

tinuous work-sheets or fan-folded webs when the latter are led over said work-sheet support and threaded through said carbon-holding blades of said groups, the bent-back leading end of the lower of said packs resting in said spacious pocket upon the body of said lower pack to permit the unhampered operation of the upper of said packs when the latter is being used in the manner of continuous billing. 70

5. In a typewriting machine, a revolute platen mounted in a displaceable swing frame, a carriage to support said swing frame, feed-rolls to co-operate with said platen, a work-presenting frame having a work-sheet support on its rear end mounted in the rear of said carriage, and a movable carbon-carrier mounted by rollers upon rails on said work-presenting frame, comprising a base furnished with a forwardly-extending operating handle and on which is mounted a plurality of groups each consisting of a plurality of carbon-holding blades with carbon-sheets attached thereto mounted upon the steps of stair-like brackets, the upper and lower of said groups being spaced far enough apart vertically and horizontally to provide a spacious opening therebetween which leads to a spacious pocket formed between two packs of continuous work-sheets or fan-folded webs when the latter are led over said work-sheet support and threaded through said carbon-holding blades of said groups, the bent-back leading end of the lower of said packs resting in said spacious pocket upon the body of said lower pack to permit the unhampered operation of the upper of said packs when the latter is being used in the manner of continuous billing. 75

6. In a typewriting machine, in combination, a revolute platen mounted in a displaceable swing frame, a movable carriage to support said swing frame, feed-rolls to co-operate with said platen, a work-presenting frame having a work-sheet support on its rear end mounted in the rear of said carriage, and a movable carbon-carrier mounted upon said work-presenting frame, comprising two groups, an upper and a lower, each composed of a plurality of carbon-holding blades mounted in steps set close together vertically, the distance between the top blade of the lower group and the bottom blade of the upper group being much greater than the distance between any two blades of either group, the distance between the foremost blade of the upper group and the rearmost blade of the lower group being correspondingly greater than the distance between any two blades of either group, thus creating a spacious pocket between the packs having a spacious opening between said groups when two separate packs of continuous work-sheets or fan-folded webs are threaded through said 80 90 95 100 105 110 115 120 125 130

carbon-holding blades, the bent-back leading end of the lower of said packs resting in said capacious pocket upon the body of said lower pack to permit the unhampered 5 operation of the upper of said packs when the latter is being used in the manner of continuous billing.

7. In a typewriting machine, in combination, a revoluble platen mounted in a displaceable swing frame, a movable carriage 10 to support said swing frame, feed-rolls to co-operate with said platen, a work-presenting frame having a work-sheet support on its rear end mounted in the rear of said 15 carriage, and a movable carbon-carrier mounted upon rails on said work-presenting frame, comprising a base on which are mounted two groups, an upper and a lower, each composed of a plurality of carbon- 20 holding blades mounted in steps set close together vertically, the distance between the top blade of the lower group and the bottom blade of the upper group being much greater than the distance between any 25 two blades of either group, the distance between the foremost blade of the upper group and the rearmost blade of the lower group being correspondingly greater than the distance between any two blades of 30 either group, thus creating a capacious pocket between the packs having a spacious opening between said groups when two separate packs of continuous work-sheets or fan-folded webs are threaded through said 35 carbon-holding blades, the bent-back leading end of the lower of said packs resting in said capacious pocket upon the body of said lower pack to permit the unhampered 40 operation of the upper of said packs when the latter is being used in the manner of continuous billing.

8. In a typewriting machine, in combination, a revoluble platen mounted in a displaceable swing frame, a movable carriage 45 to support said swing frame, feed-rolls to co-operate with said platen, a work-presenting frame having a work-sheet support on its rear end mounted in the rear of said carriage, and a movable carbon-carrier 50 mounted by rollers upon rails on said work-presenting frame, comprising a base furnished with an operating handle and on which are mounted two groups, an upper and a lower, each composed of a plurality 55 of carbon-holding blades mounted in steps set close together vertically, the distance between the top blade of the lower group and the bottom blade of the upper group being much greater than the distance between 60 any two blades of either group, the distance between the foremost blade of the upper group and the rearmost blade of the lower group being correspondingly greater than the distance between any two blades of 65 either group, thus creating a capacious

pocket between the packs having a spacious opening between said groups when two separate packs of continuous work-sheets or fan-folded webs are threaded through said carbon-holding blades, the bent-back leading end of the lower of said packs resting in said capacious pocket upon the body of said lower pack to permit the unhampered 70 operation of the upper of said packs when the latter is being used in the manner of 75 continuous billing.

9. In a typewriting machine, in combination, a revoluble platen mounted in a displaceable swing frame, a movable carriage 80 to support said swing frame, feed-rolls to co-operate with said platen, a work-presenting frame having a work-sheet support on its rear end mounted in the rear of said carriage, and a movable carbon-carrier mounted by rollers upon rails on said work-presenting frame, comprising a base furnished with a forwardly-extending operating handle, and on which are mounted two groups, an upper and a lower, each composed of a plurality of carbon-holding 85 blades mounted upon steps, set close together vertically, of stair-like brackets, the distance between the top blade of the lower group and the bottom blade of the upper group being much greater than the distance 90 between any two blades of either group, the distance between the foremost blade of the upper group and the rearmost blade of the lower group being correspondingly greater than the distance between any two 95 blades of either group, thus creating a capacious pocket between the packs having a spacious opening between said groups when two separate packs of continuous work-sheets or fan-folded webs are threaded through said carbon-holding blades, the 100 bent-back leading end of the lower of said packs resting in said capacious pocket upon the body of said lower pack to permit the unhampered 105 operation of the upper of said packs when the latter is being used in the manner of continuous billing.

10. In a typewriting machine of the continuous billing type having a displaceable platen, in combination with a work-presenting frame having a work-sheet support on its rear end and mounted on the movable carriage thereof, a movable carbon-carrier comprising two groups, an upper and a lower, each composed of a plurality of carbon-holding blades spaced far enough apart vertically and horizontally to provide a spacious opening therebetween which leads to a capacious pocket formed between two packs of continuous work-sheets or fan-folded webs made up of work-sheet units of two different sizes when they are led over said work-sheet support and threaded through said carbon-holding blades, the folded-back 115 leading end of the upper of said packs lying 120

125

130

- on top of said capacious pocket upon the body of said upper pack to permit the unhampered operation of the lower of said packs when the latter is being used in the manner of continuous billing, and the folded-back leading end of said lower pack resting inside said capacious pocket upon the body of said lower pack to permit the unhampered operation of said upper pack when it is being similarly used, it being possible to quickly change from upper to lower pack, or vice versa, for alternating or successive typing upon the different work-sheet units thereof.
11. In a typewriting machine of the continuous billing type having a displaceable platen, in combination with a work-presenting frame having a work-sheet support on its rear end and mounted on the movable carriage thereof, a movable carbon-carrier mounted upon rails on said work-presenting frame, comprising a base on which are mounted two groups, an upper and a lower, each composed of a plurality of carbon-holding blades spaced far enough apart vertically and horizontally to provide a spacious opening therebetween which leads to a capacious pocket formed between two packs of continuous work-sheets or fan-folded webs made up of work-sheet units of two different sizes when they are led over said work-sheet support and threaded through said carbon-holding blades, the folded-back leading end of the upper of said packs lying on top of said capacious pocket upon the body of said upper pack to permit the unhampered operation of the lower of said packs when the latter is being used in the manner of continuous billing, and the folded-back leading end of said lower pack resting inside said capacious pocket upon the body of said lower pack to permit the unhampered operation of said upper pack when it is being similarly used, it being possible to quickly change from upper to lower pack, or vice versa, for alternating or successive typing upon the different work-sheet units thereof.
12. In a typewriting machine of the continuous billing type having a displaceable platen, in combination with a work-presenting frame having a work-sheet support on its rear end and mounted on the movable carriage thereof, a movable carbon-carrier mounted by rollers upon rails on said work-presenting frame, comprising a base furnished with an operating handle and on which are mounted two groups, an upper and a lower, each composed of a plurality of carbon-holding blades spaced far enough apart vertically and horizontally to provide a spacious opening therebetween which leads to a capacious pocket formed between two packs of continuous work-sheets or fan-folded webs made up of work-sheet units of two different sizes when they are led over said work-sheet support and threaded through said carbon-holding blades, the folded-back leading end of the upper of said packs lying on top of said capacious pocket upon the body of said upper pack to permit the unhampered operation of the lower of said packs when the latter is being used in the manner of continuous billing, and the folded-back leading end of said lower pack resting inside said capacious pocket upon the body of said lower pack to permit the unhampered operation of said upper pack when it is being similarly used, it being possible to quickly change from upper to lower pack, or vice versa, for alternating or successive typing upon the different work-sheet units thereof.
13. In a typewriting machine of the continuous billing type having a displaceable platen, in combination with a work-presenting frame having a work-sheet support on its rear end and mounted on the movable carriage thereof, a movable carbon-carrier mounted by rollers upon rails on said work-presenting frame, comprising a base furnished with an operating handle and on which are mounted two groups, an upper and a lower, each composed of a plurality of carbon-holding blades mounted step fashion and spaced far enough apart vertically and horizontally to provide a spacious opening therebetween which leads to a capacious pocket formed between two packs of continuous work-sheets or fan-folded webs made up of work-sheet units of two different sizes when they are led over said work-sheet support and threaded through said carbon-holding blades, the folded-back leading end of the upper of said packs lying on top of said capacious pocket upon the body of said upper pack to permit the unhampered operation of the lower of said packs when the latter is being used in the manner of continuous billing, and the folded-back leading end of said lower pack resting inside said capacious pocket upon the body of said lower pack to permit the unhampered operation of said upper pack when it is being similarly used, it being possible to quickly change from upper to lower pack, or vice versa, for alternating or successive typing upon the different work-sheet units thereof.
14. In a typewriting machine of the continuous billing type, having a displaceable platen, in combination with a work-presenting frame having a work-sheet support on its rear end and mounted on the movable carriage thereof, a movable carbon-carrier mounted by rollers upon rails on said work-presenting frame, comprising a base furnished with a forwardly-extending operating handle and on which are mounted two groups, an upper and a lower, each composed of a plurality of carbon-holding blades spaced far enough apart vertically and horizontally to provide a spacious opening therebetween which leads to a capacious pocket formed between two packs of continuous work-sheets or fan-folded webs made up of work-sheet units of two different sizes when they are led over said work-sheet support and threaded through said carbon-holding blades, the folded-back leading end of the upper of said packs lying on top of said capacious pocket upon the body of said upper pack to permit the unhampered operation of the lower of said packs when the latter is being used in the manner of continuous billing, and the folded-back leading end of said lower pack resting inside said capacious pocket upon the body of said lower pack to permit the unhampered operation of said upper pack when it is being similarly used, it being possible to quickly change from upper to lower pack, or vice versa, for alternating or successive typing upon the different work-sheet units thereof.

- 6 blades mounted upon steps of stair-like brackets and spaced far enough apart vertically and horizontally to provide a spacious opening therebetween which leads to a capacious pocket formed between two packs of continuous work-sheets or fan-folded webs made up of work-sheet units of two different sizes when they are led over said work-sheet support and threaded through said 5 carbon-holding blades, the folded-back leading end of the upper of said packs lying on top of said capacious pocket upon the body of said upper pack to permit the unhampered operation of the lower of said 10 packs when the latter is being used in the manner of continuous billing, and the folded-back leading end of said lower pack resting inside said capacious pocket upon the body of said lower pack to permit the unhampered operation of said upper pack when it 15 is being similarly used, it being possible to quickly change from upper to lower pack, or vice versa, for alternating or successive typing upon the different work-sheet units 20 thereof.
15. In a typewriting machine of the continuous billing type having a displaceable platen, in combination with a work-presenting frame mounted on the movable carriage thereof and having a work-support on its rear end over which an upper and a lower pack of continuous work-sheets or fan-folded webs may be drawn, said upper pack being made up of work-sheet units which differ from those of said lower pack, said upper and lower packs to be typed upon successively or alternately one after the other, a movable carbon-carrier comprising two groups, an upper and a lower, for said upper and lower packs, respectively, each composed of a plurality of carbon-holding blades to which are fastened carbon-sheets to be interleaved between the sheets or webs of said packs, said carbon-holding blades being mounted upon the steps of stair-like brackets, said upper group being mounted far enough above and to the rear of said lower group to provide a spacious opening therebetween to admit the bent-back leading end of said lower pack into a capacious pocket formed by the bodies of said packs when said upper pack is fed underneath and around said platen for typing thereon.
- 30 16. In a typewriting machine of the continuous billing type having a displaceable platen, in combination with a work-presenting frame mounted on the movable carriage thereof and having a work-support on its rear end over which an upper and a lower pack of continuous work-sheets or fan-folded webs may be drawn, said upper pack being made up of work-sheet units which differ from those of said lower pack, said upper and lower packs to be typed upon successively or alternately one after the other, a movable carbon-carrier comprising a base provided with a forwardly-extending operating handle and mounted by rollers upon rails on said work-presenting frame and having two groups, an upper and a lower, for said upper and lower packs, respectively, each composed of a plurality of carbon-holding blades to which are fastened carbon-sheets to be interleaved between the sheets or webs of said packs, said carbon-holding blades being mounted upon the steps of stair-like brackets, said upper group being mounted far enough above and to the rear of said lower group to provide a spacious opening therebetween to admit the bent-back leading end of said lower pack into a capacious pocket formed by the bodies of said packs when said upper pack is fed underneath and around said platen for typing thereon.
- 35 17. In a web-typing machine of the class described, the combination with a platen mounted for displacement for straightening out the sheets in a pack or a folded web, of a set of carbon-blades, a carrier therefor to shift the carbon-blades along the pack of sheets, and a second set of carbon-plates mounted upon said carrier to co-operate independently with a separate superposed pack of sheets, a pocket being provided between said sets of carbon-blades in which to insert temporarily the folded-back lower pack of sheets, when required, as set forth.
